UNITED STATES PATENT OFFICE

JAMES EDGAR LEE, OF GRAND HAVEN, MICHIGAN, ASSIGNOR TO CHALLENGE MACHINERY COMPANY, OF GRAND HAVEN, MICHIGAN, A CORPORATION OF MICHIGAN

NEWSPAPER TURTLE PROOF PRESS

Application filed February 24, 1930. Serial No. 430,470.

This invention relates to a proof press, particularly useful in connection with printing proofs without the necessity of entering and locking the forms in a printing press and with which the type, illustration plates and the like are held in a chase located at the upper side of a movable truck or "turtle" as it is called, which may be moved into the machine and automatically properly located within such machine and then secured against movement, after which the type may be inked, paper drawn over the inked type and the paper pressed against the type by means of a suitable movable platen roller so as to print a proof sheet which may then be examined for mistakes or the like, the turtle which carries the chase and the make up type and illustrative plates therein being quickly and easily removed from the machine by merely rolling the same over the floor away therefrom.

This invention is concerned with many novel constructions and combinations and arrangements of parts for effectively attaining the main purpose of the invention as stated. Subsidiary thereto one important and valuable feature of this invention is that the mechanism for inking the type and pressing the paper by means of the platen roller against the inked type is of a floating character so as to conform to the chase and the type upper surfaces, within certain limits, it is not necessary at all to pay any attention to irregularities in the floor or minor differences in the height and level of the different trucks or turtles which may be introduced into the machine, or to watch out for different leveling conditions which may come from a wear of the bearings or outer surfaces of the casters on which the turtle is mounted as the floating character of the frame which carries the inking mechanism and the platen roller permits the same to conform to the surface of the type which is to be inked and against which the paper is to be pressed by the roller.

There are many other features of construction and novelty in the mechanism for the effective inking of the type and movement of the platen roller over the paper above the

type; for the elimination of ink at the upper edges of the ends and sides of the chase; for transferring ink to the type inking rollers simultaneously with the movement of the platen roller over the paper to press it against the type previously inked or, if desired, for applying and transferring ink to said type inking rollers separately and distinct from any movement of the platen roller, all of which will be apparent upon understanding the invention from the following description taken in connection with the accompanying drawings, in which,

Fig. 1 is a longitudinal vertical section through the machine of my invention showing the turtle carrying a chase disposed between the sides of the machine.

Fig. 2 is a plan view of the machine.

Fig. 3 is a transverse vertical section substantially midway between the ends of the machine and showing the turtle between the sides of the machine in elevation.

Fig. 4 is a fragmentary somewhat enlarged similar transverse vertical section illustrative of the manner in which the type inking rollers are lifted over the ends of the chase.

Fig. 5 is a fragmentary enlarged vertical section and side elevation illustrating the mechanism for applying ink to the type inking rollers.

Fig. 6 is a fragmentary plan view of the construction illustrated in Fig. 5, and

Fig. 7 is a fragmentary horizontal section illustrating a detail of the mechanism for either simultaneously or individually rotating the main inking roller from which ink is transferred to the type inking rollers.

Like reference characters refer to like parts in the different figures of the drawings.

In the construction of the machine a lower supporting frame is provided which in construction includes two substantially independent and spaced apart elongated vertical frames 1 between which the turtle or truck 95 which carries the chase with type therein is adapted to be placed. These side frames 1 are of a substantial character and are designed to be firmly located and secured on a floor; and there are substantially no cross 100

connections between said side frames except in so far as the frames are used to support the ends of a rock shaft, hereafter described.

- 5 Over the two spaced apart frames 1 a floating frame structure is mounted upon which substantially all of the mechanism for inking the type and operating the pressure platen roller is secured. This floating frame includes two elongated sides 2 located one directly over the upper end of each of the frames 1. The sides 2 of the floating frame are connected together at front and rear by cross rods 3. Various other rods and shafts, 10 on which the mechanism carried by the floating frame is mounted, also extend between the sides 2 and at what may be termed the front end of the machine are upwardly extending brackets 4, one attached to each of the sides 2 of the floating frame, over which an angular sheet metal cover 5 is disposed and secured which in practice is to serve as a support for a sheet of proof after it has been printed in the machine.
- 25 The sides 2 of the floating frame have a floating connection with the lower side frames 1 through pins 6 connected to and extending upwardly from the frames 1 into suitable sockets at the lower sides of the sides 2 of the floating frame, coiled compression springs 7 being disposed between the frame members 1 and 2 which in a measure support and balance the weight of said sides 2 of the floating frame. There are two of these pins with 30 compression springs around them at each side of the machine which are symmetrically located with respect to a central transverse plane substantially midway between the ends of the machine.
- 35 A means is provided for raising and lowering the floating frame with respect to the stationary side frames 1 below. To this end a pair of toggle links 8 are pivotally connected at their upper ends at 9, one at each side of each of the lower stationary frames 1 and at their lower ends have pivotal connection at 10 to another pair of toggle links 11 which extend downwardly and have a pin or rod 12 passing through their lower ends, at 40 the same time passing through a vertical slot 13 in a horizontal frame member of the lower stationary side frame 1. Two bars 14 are pivotally connected at 15 at their upper ends adjacent the lower side of each floating side frame member 2 and extend downwardly alongside the toggle links. The pin or rod 12 at its ends passes through the bars 14 which are continued below said pin or rod 12 between two guides 16 projecting laterally 45 from the same horizontal frame member of the side frame 1 in which the slots 13 are cut. The toggle link constructions and the bars 14 are located in a transverse vertical plane substantially midway between the planes of the pins 6 previously described.

A horizontal rock shaft 17 (see Fig. 1) extends between and is mounted at its ends on the side frames 1 to which, adjacent one of said side frames, a bell crank lever 18 is permanently secured having an upwardly extending arm 18a. An equivalent arm 18a is connected to the rock shaft 17 adjacent the other side frame 1. Rods 19 extend from the upper ends of the arms 18a to the pins 10 at the knuckles of the toggle levers described and in practice a turnbuckle adjusting nut 20 is disposed in each rod 19 so as to adjust the length of said rods as may be desired.

70 The forwardly extending arm of the bell crank lever 18 has a vertical link 21 pivotally connected at its upper end thereto which at its lower end is pivotally connected to a foot lever 22 located at the inner side of one of the lower side frame members 1 and pivotally mounted at 23 thereon at a point between the ends of said foot lever. The foot lever at its ends has outwardly extending foot engaging 75 pedals 24 and 25 which extend through openings in the frame 1 for ready operation by the foot of the operator of the machine.

80 The turtle or truck which carries the chase within the sides of which the set-up type is disposed is adapted to be rolled between the spaced apart sides of both the under supporting frame and the floating frame and under the rear cross rod 3. This truck includes a substantially horizontal top 26 supported at its corners by depending vertical posts or legs 27 which are connected by cross tubular bars 28 and longitudinal tubular bars 29. Casters or rollers are mounted at the lower ends of the legs for readily moving the turtle over the floor and into proper position with reference to the machine. On the upper side of the 85 table 26 the chase 30 is placed within which is the set-up of type plates for illustrations and the like as indicated in outline at 31, the space shown between the inner sides of the chase and the outline of the type being for the usual printer's machinery for securing and holding the type in the chase.

90 On the floor near the rear of the machine and between the sides thereof, a supporting bracket 32 is secured through the upper end of which a short shaft is mounted having a cam finger 33 connected to its front end and a foot pedal lever 34 to its rear end as shown. When the turtle has been moved to position between the sides 1 of the lower frame by 95 operating the foot pedal in one direction the cam finger is brought against the rear cross bar 28 of the turtle frame thereby securing it in position against rearward movement. The release of the turtle is accomplished by 100 operating the foot lever in the opposite direction so as to bring the cam finger below the cross rod 28 which it operatively engages.

105 When the turtle is rolled into the machine between the sides thereof one of the front corners comes against an incline 35 (see Fig. 130

2) which has the effect of moving the turtle toward the other side of the machine and brings the corners of the chase 30 located at the upper side of the turtle at its front ends under overhanging brackets 36 through which adjusting screws 37 pass, while the rear corners come under somewhat similar overhanging brackets 38 having like adjusting screws 37 passing therethrough. The 5 side of the top of the turtle opposite that at which the incline 35 engages is thereupon brought against a side gauge bar 39 (see Fig. 2) which is carried by the adjacent side 2 of the floating frame.

10 A member 40 is pivotally connected at 41 to one of the brackets 38, as shown in Fig. 2, and carries two rollers 42 and 43 adapted to engage against a side and at the outer end of the chase 30. The member 40 has a curved 15 slot 44 therein. A hand operated lever 45 passes over a supporting bracket 46 attached to and extending forward from the rear rod 3 and is pivotally mounted between its ends at 47 on the bracket, and at its front end 20 has pin 48 entering the slot 44. By turning the hand lever to the position shown in Fig. 2 the rollers 40 and 43 engage the outer end and an adjacent side of the chase 30 and move the turtle carrying the chase into proper position 25 against the gauge bar 39 and under the overhanging brackets 36 and 38 whereupon by proper manipulation by the foot lever 22 the floating frame may be lowered so that the lower ends of the adjusting screws 37 engage 30 against and securely hold the chase and the turtle on which it is located against movement.

35 The front overhanging brackets 36 are mounted on two parallel cross rods 49 which are spaced apart a short distance and on which short rollers 50 are mounted. A serrated cutting bar 51 is carried by and between the brackets. The paper 52, which is to be lead over the chase and type, is drawn 40 upwardly between the rollers 50 from a roll of paper mounted on a shaft 53 near the lower front portion of the machine, the shaft being mounted at its ends in supports 54 attached to the floor and located between the 45 spaced apart sides of the lower frame. It is evident that the paper may be drawn underneath the cutting bar 51 and over the chase and type and after the proof has been printed the paper may be cut off against the serrated 50 edge of the cutting bar 51.

55 A horizontal shaft 55 is mounted for rotation on and between the front end portions of the sides 2 of the upper floating frame. Said shaft extends through the sides and is 60 equipped with sprocket wheels 56 adjacent its ends, one end of the shaft being continued and squared for the reception of a crank whereby the shaft may be manually turned. Endless chains 57 pass around the sprocket 65 wheels 56 and lie along the outer sides of

the floating frame extending to the rear and passing around sprocket wheels 58 mounted on short stub shafts which extend through the sides of the floating frame.

In the lengths of the chains 57 vertical end 70 members 59 of a platen roller carriage are connected. A shaft 60 extends between said end members 59 and is rotatably mounted thereon on which a platen roller 61 is secured. This roller may be rubber covered if desired 75 or may be made of any suitable material such that it will properly press paper into contact with the type 31. The shaft 60, adjacent the inner sides of the end members 59 of the carriage, is also equipped with carrying rollers 80 61a which ride on the upper sides of the sides 2 of the floating frame which serve as tracks for the rollers 61a.

The carriage is completed by cross rods 62 which connect the members 59 of the carriage. On these cross rods directly in front and also back of the roller 61a are other carrying rollers 63 which ride on the upper edges of the sides 2 of the floating frame. The end members 59 extend downwardly 85 along the outer sides of the sides 2, as shown in Fig. 3, and are equipped with other rollers 64 which extend inwardly under track flanges 2a projecting outwardly from the sides 2 of the floating frame. It is evident 90 that by turning the shaft 55, the chains 57 will be actuated in unison and draw the carriage with the platen roller back and over the chase and type and, the lower surface or edge of the roller 61, being in substantially 95 the same plane as the upper sides of the chase and type, the paper will be pressed against the type. It should be noted in this connection that the length of the platen roller 61 is less than the distance between 100 the inner sides of the sides of the chase 30 so that the paper is not pressed against the upper edges of the sides of the chase but is only pressed against the type.

An inking roller 65 is carried on a horizontal shaft 66 which extends between and is mounted at its ends on the sides 2 of the floating frame. The inking roller 65 is mounted for rotation but for no other movement. A gear 67 (see Figs. 6 and 7) is secured to the shaft 66 and is in mesh with a cooperating gear 68 fixed on a short shaft 69 which is rotatably and slidably mounted through the adjacent side 2 of the floating frame, its inner end having a rotatable 110 mount in a supporting bracket 70 connected to said side 2. A spring 71 around the shaft 69 normally moves the gear 68 to clutch connect it with a combined gear sprocket wheel 72 and retaining disc 73 loosely mounted on the shaft 69 between the gear 68 and the side 2 of the floating frame. The edge of the disc 73 enters a recess in the bracket 70 to hold the wheel 72 in place. The shaft 69, at its outer end, is squared to receive a crank 115 120 125 130

and on attaching the crank, if desired, the shaft may be moved inwardly to disconnect the gears 68 and 72 whereby the inking roller 65 may be rotated without affecting any of the other mechanism.

5 A sprocket chain 74 passes around the wheel 72 and extends forwardly and upwardly therefrom to and around a sprocket wheel 75 on the shaft 55. It is evident that 10 when the shaft 55 is turned manually by attaching the crank at its end there is a simultaneous rotation of the inking roller 65 with the movement of the platen roller 61 over the machine.

15 An endless chain 76 is disposed at the inner side of each of the sides 2 of the floating frame, said chains at their rear ends passing around sprocket wheels 77 mounted near the rear ends of sides 2 and at their front ends 20 around sprocket wheels 78 secured to a cross shaft 79 which extends between and is mounted on said sides 2, one end of the shaft 79 extending through and beyond the adjacent side 2 and being squared to receive a 25 crank. The chains 76 pass above the rods 49 and their upper runs may then be directed downwardly to the sprocket wheels 78 substantially in accordance with the inclination of inwardly extending inclined tracks 80 30 formed at the inner sides integral with the sides 2 of the floating frame.

An inking roller carriage is connected with the chains 76 to be moved thereby. Each end of the carriage includes two sections 35 81 located in longitudinal alignment and pivotally connected at their adjacent ends. On the sections 81 of the carriage ends rollers 82, to traverse the upper side of said sides 2 and inclined tracks 80, are mounted. The free ends of the sections 81 are connected by cross rods 83. On these cross rods 40 inking roller supporting members 84, similar to the sections 81 and pivotally connected at their adjacent ends, are mounted. On and between the parts 84 two pairs of inking 45 rollers 85 are disposed and rotatably mounted as best shown in Fig. 2. Ink spreading rollers 86, one for each pair of inking rollers 85, are located above and between each pair of inking rollers and mounted at their ends on the respective parts 84 50 from which inclined cam members 87 project to engage with the similar cam like ends of the spreading rollers 86 whereby when the rollers 86 are rotated by frictional contact with the inking rollers 85 they are also simultaneously reciprocated short distances.

When the type inking rollers 85 are to be inked from the main inking roller 65, the 55 shaft 79 is turned so as to bring the type inking roller carriage onto the inclined tracks 80 with the inner rollers 85 of the two pairs of type inking rollers bearing against the surface of the main inking roller 85 as shown in Fig. 5. Turning the roller 65 causes a turn-

ing of the rollers 85 in contact therewith while the other rollers 85 are driven from the first rollers 85 through the spreading rollers 86 and the ink on the surface of the main inking roller 65 is carried to the type inking 70 rollers 85 and through the reciprocatory action of the spreading rollers 86 and type inking rollers 85 are evenly covered on their surfaces with ink.

In order to hold the type inking carriage 75 against movement during the inking operation one section 81 thereof is provided with an upwardly extending dog 88 with which a latch dog 89 is adapted to engage. The latch dog is on one arm 90 of a bell crank lever 80 which is mounted for pivotal movement at 91 on the adjacent side 2 of the machine and has a downwardly extending arm 92 with an outwardly projecting finger engaging portion 93 for the operator to release the latch when the 85 inking operation has been performed and it is desired to move the type inking rollers back over the machine to ink the type 31.

The type inking rollers on their rearward movement for the purpose of inking the type 90 31 must pass over the ends of the chase 30, the upper sides of which are in the same horizontal plane with the type. In order that ink 95 will not be transferred to the upper sides of the ends of the chase, raised projections or 100 bumps 94 are secured to the upper sides of the sides 2 of the floating frame for the carriage 105 rollers 82 to ride over and are positioned so that the type inking roller carriage is lifted to raise the type inking rollers 85 above the ends of the chase but permitting the type inking 110 rollers to come back to lower position when the type 31 is reached thereby keeping the upper sides of the ends of the chase free of ink at all times yet causing the face of the type to be completely inked with the passage 115 of the type inking roller carriage. It will be also noted that the length of the type inking 120 rollers 85 is less than the distance between the inner sides of the sides of the chase so that no ink is applied to the upper sides of the sides of the chase and, therefore, when paper 125 is put over the type and chase and the platen roller carried over the paper to press it against the type, no ink is transferred from the chase to the paper.

This construction of proof press described is one which has proved very practical and successful. The turtles or trucks, each with a top 26, which may be an imposing table, are very readily rolled into the machine between its sides, quickly secured in proper position and, due to the floating character of the upper frame of the machine on which all of the essential mechanism of the machine is mounted, variations in the heights and levels of the 130 imposing table 26 and the chase and type thereon are automatically taken care of as the floating frame with its mechanism when lowered, is brought to rest against the upper

sides of the chase at its corners when the adjusting screws 37 engage thereagainst. The inking of the inking rollers may be accomplished by itself by engaging the shaft 69 with a crank and pushing the same inwardly, as is desirable when the inking of the type for the first proof sheet is to be done. The inking roller carriage is then moved to the rear over the type. Then when the type inking roller carriage is moved back to the position shown in Figs. 1 and 5, latched in position, by turning the shaft 55 the platen roller is moved back over the paper which in the meantime has been drawn upwardly and over to the rear to cover the inked type and at the same time the type inking rollers 85 are again inked for the next succeeding operation. After the platen roller has performed its function and has been returned to the front 20 of the machine, the proof sheet printed is severed by engaging the paper against the serrated knife edge at 51 and thrown upwardly over the sheet metal plate 5, the turtle released and run out of the latch, the next one 25 put in its place and the operation repeated as many times as may be necessary.

The invention is capable of embodiment with many variations in specific detail of construction from that shown in the drawings 30 and is not to be limited specifically thereto. The invention is defined in the appended claims and is to be considered comprehensive of all forms of structure coming within their scope.

35 I claim:

1. In a machine of the class described, a lower supporting frame having spaced apart vertical sides, an upper floating frame mounted above the sides of the supporting frame whereby a truck carrying type or the like in a chase may be moved between the sides of the two frames, type inking mechanism movably mounted on said floating frame to traverse the same and pass over and ink the 40 type, a platen roller carriage carrying a platen roller mounted on the floating frame to traverse the same and to press paper against the inked type, and manually operable mean for independently moving the 45 type inking mechanism and the platen roller carriage.

2. In a machine of the class described, a supporting frame having spaced apart vertical sides, a floating frame mounted above 55 the sides of the supporting frame having spaced apart sides whereby a truck provided with a horizontal top may be freely moved between the sides of the two frames, said top of the truck being adapted to support a chase 60 with type or the like therein, means for raising and lowering the floating frame, means on the floating frame to engage with said chase on lowering the floating frame to thereby properly position the floating frame 65 and mechanism carried thereby with refer-

ence to said chase and type therein, type inking mechanism mounted on the floating frame to traverse the same lengthwise thereof and ink the type, and a platen roller carriage with a platen roller thereon mounted on the floating frame to traverse the same and moved back and forth over said type and chase. 70

3. A construction containing the elements in combination defined in claim 2, combined with means on the floating frame adapted to engage the top of the truck and automatically move it to proper position when the truck is moved between the sides of said supporting and floating frames, and means for releasably securing the truck in said position after it has 80 been moved thereto.

4. In a machine of the class described, a supporting frame having spaced elongated vertical sides, a floating frame movably mounted above the sides of the supporting frame, means mounted on the sides of the supporting frame and connected therewith for raising and lowering the floating frame, a type inking mechanism carried by the floating frame, means on said floating frame with 85 which said type inking mechanism is connected for moving the same back and forth lengthwise of the floating frame, a platen roller carriage and a platen roller carried thereby mounted on the floating frame to 90 traverse the same lengthwise thereof, and means carried by the floating frame connected with said platen roller carriage for moving the same.

5. In a machine of the class described, a lower supporting frame having spaced apart elongated parallel sides, a floating frame having spaced apart elongated parallel sides mounted above the supporting frame, connections between the sides of the two frames 100 operative for raising and lowering the floating frame with respect to the lower frame, endless chains mounted at the sides of the floating frame, a type inking roller carriage connected in the length of said chains and movable therewith, a platen roller carriage carrying a platen roller mounted to traverse the upper sides of the sides of the floating frame, and other endless chains located 105 lengthwise of the sides of said floating frame with which said platen roller carriage is connected for moving said carriage back and forth lengthwise of the floating frame.

6. In a machine of the class described, a supporting frame having elongated spaced apart parallel sides, a floating frame having elongated parallel spaced apart sides located above the sides of the supporting frame whereby a truck or turtle may be moved to a position between the sides of the two frames, a chase with type set therein carried by said truck, means for raising and lowering the floating frame with respect to the supporting frame and truck, devices carried by the floating frame extending over the corners of said 115 120 125 130

chase to bear thereagainst when the floating frame is lowered, paper guide means on said floating frame at the front end of the truck through which paper may be drawn over the type, a type inking mechanism mounted on the floating frame to move back and forth lengthwise thereof over said type, means for manually moving said type inking means, and means for pressing the paper against the inked type mounted to move back and forth lengthwise of and on said floating frame.

7. In a machine of the class described a frame having spaced apart sides, type inking mechanism mounted on said frame and movable to traverse the same back and forth lengthwise thereof, said frame being adapted to bear against the upper side of and be supported by a type holding chase, and means to press paper against the type movably mounted to traverse said frame back and forth lengthwise thereof.

8. A machine of the class described including an upper frame, means thereon for resting the same against the corners of a type holding chase, endless chains mounted lengthwise of said frame at each side thereof, a type inking roller carriage with type inking rollers thereon moved by said chains lengthwise of the frame over said type and chase, other endless chains mounted lengthwise of said frame at the sides thereof, a platen roller carriage and a platen roller thereon moved by said chains back and forth over said type and adapted to press paper against the type and means for manually operating said chains.

9. A construction containing the elements in combination defined in claim 8, combined with a main inking roller mounted between the sides of the frame to which the rollers on said type of inking roller carriage may be brought to supply ink thereto, means for turning said main inking roller and means for lifting the type inking rollers over the ends of the chase when brought thereto.

10. In a machine of the class described, a lower supporting frame, an upper floating frame mounted on the lower frame and adapted to be raised and lowered with respect thereto, means for raising and lowering the upper frame, a pair of chains mounted lengthwise and alongside of the sides of the upper frame a carriage provided with a plurality of type inking rollers connected with, lying between and movable by said chains, a main inking roller mounted between the sides of the upper frame toward one end thereof to which the type inking rollers may be brought, and means for rotating the main inking roller, manually operable means for moving said chains to carry the type inking roller carriage to the main inking roller or lengthwise of said upper frame.

11. A construction containing the elements in combination defined in claim 10, combined

with additional endless chains located lengthwise of the sides of said upper frame, a carriage connected with said additional chains and movable over the upper sides of the frame, a platen roller carried by said carriage, means for driving said additional chains to carry the carriage and platen roller back and forth lengthwise of said upper frame, and means to drive the main inking roller simultaneously with the movement of said carriage.

12. In a machine of the class described, a lower supporting frame having spaced apart sides, an upper floating frame having spaced apart sides located above the sides of the supporting frame whereby a truck having a horizontal top and carrying a chase with type therein may be moved to a position between the sides of said frames, means mounted on the sides of the lower frame and connected with the upper frame for raising and lowering said upper frame, means mounted on one side of the upper frame for automatically positioning the truck to bring its top and the chase carried thereon against the opposite side of the upper frame and to a predetermined forward position, means for holding the truck in the position to which it has been moved, inking means mounted on the upper frame to traverse the same and pass over said type in the chase and ink the same, paper guide means at one end of said chase through which paper may be drawn to lie over the inked type, and means mounted for movement lengthwise of the frame to press the paper against the type.

13. A construction containing the elements in combination defined in claim 12, combined with means mounted at the upper sides of the said sides of the upper frame for lifting the inking means over the ends of the chase when it comes thereto.

14. In a construction of the class described, a supported floating frame having spaced apart sides between which the upper horizontal top of a truck carrying a chase with type therein may be positioned, means for raising and lowering said supporting frame, means projecting from said floating frame to bear against the upper sides of said chase when said frame is lowered to thereby position the frame with respect to the upper sides of the chase and type therein, a main inking roller mounted between the sides of the frame near one end thereof, a type inking roller carriage mounted to move lengthwise of said frame, means for moving the same back and forth over the frame and to said main inking roller, type inking rollers on said carriage adapted to be brought into contact engagement with the main inking roller, means for rotating the main inking roller, and a releasable latch for holding the type inking roller carriage against movement when its rollers are in contact with the main inking roller.

15. In a machine of the class described, a frame having spaced apart sides, a main inking roller mounted for rotation between the sides of the frame toward one end thereof, two endless chains located one lengthwise of each side of the frame, a carriage mounted on said frame to travel lengthwise thereof connected with said chains, means for simultaneously rotating said inking roller and operating said chains to move the carriage over the frame, a platen roller carried by said carriage, two additional endless chains mounted lengthwise of and one at each side of the frame, a type inking roller carriage carrying type inking rollers connected with said additional chains and moved thereby lengthwise of the frame or into operative engagement with the main inking roller and independent means for operating said additional chains to move the type inking rollers and carriage therefor.

16. A construction containing the elements in combination defined in claim 15, combined with means for disconnecting said main inking roller from the means operating the first chains and for independently turning said inking roller.

17. In a machine of the class described, a lower supporting frame having spaced apart vertical sides, an upper floating frame mounted above the sides of the supporting frame whereby a truck carrying type or the like in a chase may be moved between the sides of the two frames, a platen roller carriage carrying a platen roller mounted on the floating frame to traverse the same and to press paper against the type, and manually operable means for moving the platen roller carriage.

18. In a machine of the class described, a supporting frame having spaced apart vertical sides, a floating frame mounted above the sides of the supporting frame having spaced apart sides whereby a truck provided with a horizontal top may be freely moved between the sides of the two frames, said top of the truck being adapted to support a chase with type or the like therein, means for raising and lowering the floating frame, means on the floating frame to engage with said chase on lowering the floating frame to thereby properly position the floating frame and mechanism carried thereby with reference to said chase and type therein, and a platen roller carriage with a platen roller thereon mounted on the floating frame to traverse the same and moved back and forth over said type and chase.

19. In a machine of the class described, a frame supported for movement in a vertical direction and adapted to receive a truck carrying type, said truck being supported independently of said frame, means for moving said frame vertically relative to the type on said truck, means on said frame engageable with said type to accurately limit the move-

ment of the frame relative to the type to a predetermined position and a platen roller traversably mounted on and guided by the frame and movable over the face of the type.

20. In a machine of the class described, a frame supported for movement in a vertical direction and adapted to receive a truck carrying type, said truck being supported independently of said frame, means for moving said frame vertically relative to the type on said truck, adjustable means on said frame engageable with said type to accurately limit the movement of the frame relative to the type to a predetermined position and a platen roller traversably mounted on and guided by the frame and movable over the face of the type.

21. A machine of the class described comprising, a frame, means for supporting said frame for vertical movement and for change of its horizontal plane, said frame being adapted to receive a truck carrying type, said truck being supported independently of said frame, means for moving said frame vertically, means on said frame engageable with said type at a plurality of locations to accurately limit the movement of the frame relative to the type to a predetermined position and a platen roller traversably mounted on said frame and guided thereby and movable over the face of said type.

22. A machine of the class described comprising, a frame, means for supporting said frame for vertical movement and for change of its horizontal plane, said frame being adapted to receive a truck carrying type, said truck being supported independently of said frame, means for moving said frame vertically, adjustable means on said frame engageable with said type at a plurality of locations to accurately limit the movement of the frame relative to the type to a predetermined position and a platen roller traversably mounted on said frame and guided thereby and movable over the face of said type.

In testimony whereof I affix my signature.
JAMES EDGAR LEE.
